CREASE PREVENTING TIE HOLDER.

Samuel Hoffman, Brooklyn, N. Y.

Application September 25, 1942, Serial No. 459,734

1 Claim. (Cl. 206—79)

This invention relates to new and useful improvements in a crease preventing tie holder.

More specifically, the invention proposes the construction of a crease preventing tie holder characterized by a trapezoidal cardboard adapted to form a support for four-in-hand ties which have been folded in half and engaged over the top end thereof with a band of paper being engaged about the cardboard and ties in a manner to retain the ties in position upon the cardboard.

Another object of this invention proposes mounting a cylindrical member upon the top end of the trapezoidal cardboard to be disposed within the bend of the adjacent tie in a manner to prevent the ties from being creased flat against the top end of the cardboard.

Still another object of the invention proposes various means for securely mounting the cylindrical member in position upon the top end of the cardboard in a manner to be in position thereon so that the ties may be engaged thereover.

It is a further object of this invention to construct a crease preventing tie holder which is simple and durable and which may be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a perspective view of a crease preventing tie holder constructed in accordance with this invention and having ties in position thereon.

Fig. 2 is an elevational view of the top end of the holder per se.

Fig. 3 is an enlarged vertical sectional view taken on the line 3—3 of Fig. 2.

Fig. 4 is a view similar to Fig. 2 but illustrating a modification of the invention.

Fig. 5 is an enlarged vertical sectional view taken on the line 5—5 of Fig. 4.

Fig. 6 is a perspective view of one end of the cylindrical member used in the form of the invention shown in Fig. 4.

Fig. 7 is another view similar to Fig. 2 but illustrating a still further modification of the invention.

Fig. 8 is an enlarged vertical sectional view taken on the line 8—8 of Fig. 7.

Fig. 9 is an elevational view of the top end of the cardboard member per se as used in the form of the invention shown in Fig. 7.

Fig. 10 is a perspective view of Fig. 9 with the end of the cardboard separated as permitted by the slit.

Fig. 11 is a perspective view of the cylindrical member used in the form of the invention shown in Fig. 7.

The crease preventing tie holder, according to this invention, includes a trapezoidal cardboard 10 adapted to form a support for ties 11. The ties 11 are first bent in half and then superimposed one on the other and engaged over the top end of the cardboard 10. A band of paper 12 is engaged about the cardboard 10 and the ties 11 and has its ends secured together in a manner to retain the ties 11 in position upon the cardboard 10.

A cylindrical member 13 is mounted on the top end of the cardboard 10 and is disposed within the bent portion of the adjacent tie. The cylindrical member 13 is formed of wood and has a groove 14 extended inwards from one side thereof. The top end of the cardboard is extended into the groove 14 and mucilage 15 holds the cylindrical member 13 in position upon the top end of the cardboard 10.

The cylindrical member 13 provides a rounded surface over which the ties extend and prevents them from being folded flat against the top end of the cardboard 10.

In Figs. 4 to 6 the groove 14 in the cylindrical member 13 continues at its inner end into an enlarged base groove 14a. The top end 16 of the cardboard 10 is bent downwards and the top end of the cardboard is adapted to be slipped into one of the cylindrical member 13 from one end thereof. When this is done the bent down portion 16 will be disposed within the enlarged base groove 14a preventing the cylindrical member 13 from dropping off the end of the cardboard 10.

The cardboard 10 is of a width to have its top corners projected beyond the ends of the cylindrical member 13. These top corners are then bent forwards as shown in Fig. 4 so as to prevent the cylindrical member from sliding off the cardboard 10.

In other respects this form of the invention is similar to the previous form and like reference numerals identify like parts in each of the several views.

In Figs. 7 to 11, the crease preventing tie holder is characterized by a cardboard 10' over which ties not shown on the drawing are adapted to be engaged. A tubular member 13' is mounted on the top end of the cardboard 10' and is disposed within the bent portion of the adjacent tie

to prevent the ties from being folded flat against the top end of the cardboard 10'.

The cardboard 10' has a portion of its top end cutaway forming spaced lugs 20 which extend along the ends of the tubular member 13'. Projections 21 are extended inwards from the inner sides of the lugs 20. The projections 21 are projected into the ends of the tubular member 13' for holding the tubular member in position upon the top end of the cardboard 10'.

A slit 22 is extended downwards from the base of the cutaway top end of the cardboard 10'. This slit 22 permits the lugs 20 to be bent away from each other as shown in Fig. 10 to increase the distance between the inner ends of the projections 21 permitting the projections to be easily extended into and removed from the ends of the tubular member 13'. The tubular member 13' in the form of the invention is preferably a length of cardboard tubing.

While I have illustrated and described the preferred embodiments of my invention, it is to be understood that I do not limit myself to the precise constructions herein disclosed and the right is reserved to all changes and modifications

coming within the scope of the invention as defined in the appended claim.

Having thus described my invention, what I claim as new, and desire to secure by United States Letters Patent is:

A crease preventing tie holder, comprising a cardboard adapted to form a support for four-in-hand ties bent at their centers and engaged over the top end thereof, and a cylindrical member mounted on said top end and disposed within the bent portion of the adjacent tie, said cylindrical member being formed with a groove into which the top end of said cardboard is extended, said groove continuing at its inner end into a base groove extending substantially at right angles thereto, and said cardboard having its top end bent downwards and disposed within said base groove locking said cylindrical member in position on the top end of said cardboard, said cardboard having its top corners bent forwardly at the ends of said cylindrical member preventing said cylindrical member from moving laterally relative to said cardboard.

SAMUEL HOFFMAN.
